UNITED STATES PATENT OFFICE.

GEORGE H. PENNINGTON AND WINTHROP WITHEROW, OF BEAVER FALLS, PENNSYLVANIA.

BRUSH.

937,640.

Specification of Letters Patent. Patented Oct. 19, 1909.

Application filed March 12, 1909. Serial No. 482,892.

To all whom it may concern:

Be it known that we, GEORGE H. PENNINGTON and WINTHROP WITHEROW, citizens of the United States of America, residing at Beaver Falls, in the county of Beaver and State of Pennsylvania, have invented certain new and useful Improvements in Brushes, of which the following is a specification, reference being had therein to the accompanying drawing.

This invention relates to brushes, and the primary object of our invention is to provide a brush with a novel case for inclosing the same.

Another object of this invention is to provide a simple and durable article that can be advantageously used by travelers and easily carried in the pockets for use when desired.

A further object of this invention is to provide a brush with a novel casing for inclosing the brush, said casing being provided with means whereby it can be attached to the brush to serve functionally as a handle.

We attain the above objects by a brush that will be hereinafter described in detail and then specifically claimed, and reference will now be had to the drawing forming a part of this application, wherein there is illustrated the preferred embodiments of our invention, but we would have it understood that the detail construction thereof can be varied or changed without departing from the spirit of the invention.

In the drawings:—Figure 1 is a side elevation of the brush in position for use, Fig. 2 is a longitudinal sectional view of the same, Fig. 3 is a similar view illustrating the brush inclosed by a housing and casing, Fig. 4 is a horizontal sectional view of the same, looking at the back of the brush, and Fig. 5 is a cross sectional view of the brush, inclosed by the housing and casing, the section being taken at right angles to the sectional view shown in Fig. 3.

In the drawings, 1 designates a metallic casing having an open end 2 and an open bottom. Oppositely disposed sides of said casing are bent to provide interior confronting longitudinal guide grooves 3. Detachably mounted in the metallic casing 1 is a metallic housing 4 having the oppositely disposed sides thereof provided with longitudinal exterior ribs 5 adapted to slide in the grooves 3 and retain said housing in

engagement with the casing 1. One end of the housing 4 on the inner side thereof adjacent to the longitudinal sides of said housing is provided with parallel metallic clips 6, while the opposite end of the housing is provided with a single central lug 7 and a clamp, said clamp comprising flat springs 8 connected by a yoke 9, and to provide clearance for the yoke 9, the edge of the housing is cut away, as at 10.

11 designates a brush back having bristles 12 and one end of said back is adapted to be held between the parallel clips 6, while the opposite end is adapted to rest upon the central lug 7 and be retained thereon by the ends of the yoke 9 extending over the end of the back 11. The longitudinal sides of the brush back 11 are recessed, as at 13, to provide finger grips, while the longitudinal sides of the housing 4 at the upper edges thereof are cut away, as at 14, to provide clearance for fingers gripping the back of the brush.

As shown in Fig. 3 of the drawings, the brush is retained within the housing by the clips 6, lugs 7, and the clamp of said housing, and with the housing in the casing 1, the brush is fully protected. To place the brush in a useful position, the housing is removed from the casing and the clamp 9 moved to release the brush. By inverting the brush, the back 11 thereof can be again placed in engagement with the clips 6, lug 7 and the clamp, as shown in Fig. 2 of the drawings, and the housing replaced within the casing, whereby the casing will serve functionally as a handle or the back of the brush.

In connection with the casing 1, we can use a mirror 15, said mirror being retained in engagement with the casing 1 by a flange 16 soldered or similarly secured to said casing.

By using the housing and the brush in the position shown in Fig. 2 and detached from the casing, said casing can be held whereby the operation of the brush in the hair can be observed in the mirror.

Having now described our invention, what we claim as new, is;

1. A device of the character described, comprising a casing having an open end, a housing slidably mounted in said casing, a brush arranged within said housing, means for detachably mounting said brush within

said housing, said means including clips at one end of said housing for engaging the back of the brush, a lug and a spring clamp at the opposite end of said housing for engaging the other end of the back of the brush, substantially as described.

2. A device of the character described, comprising a casing having an open end and further having the opposite sides thereof 10 provided with longitudinal grooves, a housing having longitudinal ribs slidably mounted in the grooves in the casing, a brush de-

tachably mounted in said housing, clips carried by the housing for receiving one end of the brush, and a spring clamp at the opposite end of the housing for holding the other end of the brush back. 15

In testimony whereof we affix our signatures in the presence of two witnesses.

GEORGE H. PENNINGTON.
WINTHROP WITHEROW.
